UNITED STATES PATENT OFFICE.

VICTOR D. LESPINASSE, OF CHICAGO, ILLINOIS.

INSTRUMENT FOR REMOVING THE TESTICLES OF BIRDS.

Application filed June 26, 1922. Serial No. 571,080.

To all whom it may concern:

Be it known that I, VICTOR D. LESPINASSE, a citizen of the United States, residing at Chicago, in the county of Cook and State 5 of Illinois, have invented a new and useful Instrument for Removing the Testicles of Birds, of which the following is a specification.

The object of my invention is to provide 10 an easily made and inexpensive instrument for seizing and raising intact a testicle of a bird away from the large blood vessels on which it rests, and twisting the blood vessels attaching said testicle to the back into a 15 cord which can be easily cut and the testicle removed.

I attain these objects by the mechanism illustrated in the accompanying drawing, in which Fig. 1 is a view in perspective of the 20 instrument being manipulated with a testicle attached thereto; and Fig. 2 is a view in perspective of the instrument alone.

Similar letters of reference refer to similar parts throughout the several views.

25 The instrument comprises a handle *a*, which may be made of metal or other suitable material, at one end of which a loop or eye *b* is formed, of suitable size to pass over the testicle of the bird. I have shown this 30 eye *b* as formed by making one end of the instrument of twisted wires *c* and *d*, made onto or attached to the handle *a*, which wires *c* and *d* are spread apart to form said eye *b*. Extending from the eye *b* and 35 communicating therewith, and preferably closed at its outer end, is a slot *e*, adapted to permit the passage of the blood vessels attached to the testicle through it and hold the testicle firmly while it is being twisted. This slot *e* may be conveniently formed as illustrated, i. e., by having it 40 formed of the same wires *c* and *d*, which are attached to the handle *a* and spread to form the eye *b*.

45 To assist in the manipulation of the instrument I have found it better to have the plane of the part bearing the slot *e* formed at an angle, preferably a right angle, to the plane of the part bearing the eye *b*, but this is not 50 essential.

The method of operation of the instrument is as follows: The bird is bound and held, an incision made between its last two ribs, the edges of the cut spread and access 55 to the testicles obtained in the customary manner.

The testicle being now exposed, my instrument is held by the handle, as illustrated in Fig. 1, it being held lightly as a pen would be held. It is put down into the cut, preferably being pointed toward the bird's head. The testicle *f* is then threaded through the eye *b* of the instrument from the head of the bird toward the tail. No force is necessary to do this. If any force appears necessary the testicle is not going on properly and the direction of the instrument should be changed. The testicle can be threaded on the instrument from the tail to the head if preferred.

After the testicle has gone through the eye *b* of the instrument the instrument is still drawn so that the blood vessels attached to the testicle enter the slot *e* and the testicle is firmly fixed on the upper edge of said slot, as shown in Fig. 1. Then the instrument is continuously pulled toward the operator and continually twisted, this gradually bringing the testicle up out of the cut and twisting the blood vessels *g* attaching it to the back into a cord which can now be cut with scissors or knife in the usual way.

When this has been done the cut is closed as is usual in such operations.

My invention has particular reference to the caponizing of chickens, but the instrument can, of course, be used in any other instance where removal of the testicles from any bird is desired.

Having now described my invention, what I claim as new and desire to secure by Letters Patent of the United States is—

1. An instrument for seizing and raising the testicle of a bird, comprising a handle and a member having an eye and a slot communicating with the said eye, substantially as described.

2. An instrument for seizing and raising the testicle of a bird, comprising a handle and a member having an eye and a slot closed at one end and communicating at the other end with said eye, substantially as described.

3. An instrument for seizing and raising the testicle of a bird, comprising a handle and a member having an eye and a slot communicating with the said eye, the plane of the portion of said member bearing said slot being at an angle with the plane of the portion of said member bearing said eye, substantially as described.

4. In an instrument for seizing and rais-

ing the testicle of a bird, a handle comprising a pair of spaced members having converging portions remote from said handle, and a pair of substantially parallel portions in which said converging portions respectively terminate.

5. In an instrument for seizing and raising the testicle of a bird, a handle, a pair of spaced members having converging portions remote from said handle, and a pair of substantially parallel portions in which said converging portions respectively terminate, 10 said parallel portions being joined together

at their ends remote from said converging portions.

6. In an instrument for seizing and raising the testicle of a bird, a handle, a pair of spaced members having converging portions remote from said handle, and a pair of substantially parallel portions in which said converging portions respectively terminate, 20 said parallel portions extending at an angle to the plane of said converging portions and being joined together at their ends remote from said converging portions.

VICTOR D. LESPINASSE.
